United States Patent Office
UNITED STATES PATENT OFFICE.

EDWARD PIERSON, OF CLARKE STATION, INDIANA.

NECKTIE-STRETCHER.

1,253,720. *Specification of Letters Patent. Patented Jan. 15, 1918.*

Application filed December 20, 1916. Serial No. 137,985.

To all whom it may concern:

Be it known that I, EDWARD PIERSON, a citizen of the United States, residing at Clarke Station in the county of Lake and State of Indiana, have invented certain new and useful Improvements in Necktie-Stretchers; and I do hereby declare the following to be a full, clear, and exact description of the invention, such as will enable others skilled in the art to which it appertains to make and use the same.

This invention relates to improvements in necktie stretchers.

The object of this invention is the provision of a necktie stretcher in which is embodied a frame, retaining rollers supported in the frame, a supporting rod in the frame and located below the retaining rollers and means carried by the retaining rollers cooperating with means located in the frame for holding the rollers against rotation in one direction when neckties are placed thereon.

A still further object of this invention is the provision of a frame in which a plurality of neckties may be placed and stretched at one time thus removing the wrinkles and creases from the ties and consequently prolonging the life of the ties.

A still further object of this invention is the provision of a frame in which are positioned a plurality of retaining rollers which are adapted to be rotated in opposite directions and novel means arranged in the frame and engaging said rollers to hold the latter against reverse rotation, and clamping rings arranged on the retaining rollers.

Another object of this invention is to so arrange the clamping rings on the retaining rollers whereby the ends of the ties may be secured by the clamping rings to the rollers thus holding the ties taut at all times.

A still further object of this invention is to provide a necktie stretcher of this character which shall be simple, practical, and comparatively inexpensive in construction, and one that can be manufactured and sold at a comparatively low cost.

With these and other objects in view the invention consists in the novel combination and arrangement of parts hereinafter more fully described and set forth in the claims hereto appended.

In the drawings:

Figure 1 is a front elevation of my im-

proved tie stretcher with the lower part of the frame omitted.

Fig. 2 is a vertical sectional view of the same.

Fig. 3 is a fragmentary sectional view taken on the line 3—3 of Fig. 1.

Fig. 4 is an enlarged sectional view of one of the retaining rollers illustrating the clamping ring or band.

Fig. 5 is a front elevation partly broken away illustrating a modified form of my invention.

Fig. 6 is a sectional view of one of the rollers in the modified form.

Fig. 7 is a front elevation partly broken away illustrating another modified form of this invention.

Like numerals of reference designate corresponding parts in all the figures of the drawings.

Referring more particularly to the drawings, the numeral 1 designates a supporting frame which comprises in its construction spaced side bars 2 and the connecting end bars 3. The end bars 3 are secured to the upper and lower ends of the side bars 2 and provide a rectangular frame.

The side bars 2 are provided near their upper ends with a pair of relatively spaced superposed openings in which the ends of the shafts 4 are secured. Rotatably mounted upon the shafts 4 are the retaining rollers 4 and 5. The retaining rollers 4 and 5 are each provided at their opposite ends with ratchet wheels 6 and 7 and are adapted for rotation independently of one another. The retaining rollers are rotatably mounted upon the shafts 4 and are located wholly within the side bars 1 as clearly shown in Fig. 1 of the drawings.

The retaining rollers of one shaft are arranged in superposed relation and are at a relatively spaced distance from the retaining rollers on the other shaft so as to permit the free rotation of all the rollers independently of one another.

A plurality of retaining jaws 8 and 9 are arranged in pairs and each pair is pivotally secured as at 10 to the inner face of the side bars 2 of the frame 1 as clearly shown in Fig. 1 of the drawings. The jaws 8 and 9 are arranged in pairs and each pair arranged in superposed relation and the forward ends of each pair of the jaws are

twisted as at 11 to provide engaging members which are adapted to engage the teeth of the ratchet wheels carried by the retaining rollers and hold the rollers against rotation in one direction.

A supporting rod 13 is secured transversely across the frame 1 and has each of its ends secured in one side bar 2 of the frame 1, and the supporting rod 13 is located adjacent the lower ends of the side bars 2 as clearly shown in Fig. 2 of the drawings.

A plurality of clamping bands or rings 14 formed of flat spring sheet metal are arranged on each of the retaining rollers, and the clamping bands 14 have their ends overlapped and their inner ends secured each to its respective roller by screws 15 or other suitable fastening means, which means extend through the inner end as clearly shown in Fig. 4 of the drawings. The free end of the bands 14 located beyond the fastening member 15 are adapted to be bent to lie in close proximity to the body of the band and this forwardly extending portion constitutes a retaining member 16. The retaining member 16 is adapted to lie in close proximity to the body of the band due to its resiliency obtained by the use of flat spring metal and this retaining member is adapted to firmly clamp one end of a necktie inserted thereunder, thus permitting the rollers to be rotated securing the necktie thereabout and holding the same taut and stretched at all times.

The clamping bands 14 are secured to each of the rollers, but are reversely arranged on the upper and lower sets of rollers, the purpose of which will be hereinafter more fully described.

The bands which are secured on the rollers 4 which are the lower rollers are located in the rear of the frame and have their retaining members 16 extending rearwardly while the bands 14 which are secured on the upper rollers 5 have their retaining members 16 extending forwardly, thus it can be readily seen that one end of the ties are secured to the upper rollers and their opposite end to the lower rollers and the rollers rotated in a reverse direction and the fastening members placed into engagement with their respective ratchet wheel, thus holding their roller against rotation in the opposite direction and holding the ties stretched and taut at all times.

In Figs. 5 and 6 of the drawings, there is disclosed a modified form of my invention which comprises in its construction a frame 60 having side bars 2' and end connecting bars 3'. The rollers in the frame are formed into sections 17 and 18, and are hingedly connected together by a pair of hinges 19 which are secured near the opposite ends of the sections along one of their longitudinal

edges as at 20. The opposite longitudinal edges are provided with a suitable fastening means designated 21 which firmly clamp the opposing flat faces of the sections together for firmly securing the ends of a necktie therein.

The rollers or sections 17 and 18 are secured in the frame in any desirable manner but the ends of one section is preferably provided with trunnions (not shown) which trunnions are secured in the side bars 2' of the frame. The sections and their fastening means do away with the clamping bands or rings, but the operation of this modified form is identical with the preferred form.

In Fig. 7 I have disclosed another modified form which comprises the side bars 22 which have journaled adjacent their upper ends and arranged transversely there across the shafts 23, which are arranged in spaced relation one above the other. The shafts 23 have journaled thereon a plurality of retaining rollers 24, each roller provided with a ratchet wheel 25, which ratchet wheel is secured to one end thereof and is journaled about the shaft 23. A supporting rod 26 is journaled transversely across the frame 1 and has its ends secured in the side bars 22 and this supporting bar is located in the frame 1 and centrally between the shafts 23. Pivottally mounted upon the supporting bar 26 and arranged in pairs are the jaws 27, each jaw being twisted near its forward end as at 28 and its extreme end is adapted to engage one ratchet wheel for holding one roller against rotation in one direction. It will be understood that one jaw of each pair is adapted to engage one ratchet wheel of one roller thus holding its respective roller against rotation in one direction when held under tension by a necktie.

The rollers 24 are adapted to have clamping bands 14 secured thereon which clamping bands are illustrated in the preferred form of the invention.

What is claimed is:

1. A necktie stretcher comprising a frame, a supporting rod located in the frame, a pair of relatively spaced superposed shafts journaled in the frame, a plurality of retaining rollers carried by the shafts, means for holding the rollers from rotation in one direction, and clamping means carried by each roller.

2. A necktie stretcher comprising a frame, a supporting rod journaled in the frame adjacent the lower end thereof, a pair of spaced superposed shafts secured in the frame adjacent the upper end thereof, retaining rollers rotatably mounted on the shafts, a ratchet wheel carried by each of the retaining rollers, means pivotally mounted in the frame and associated with the ratchet wheels of the rollers for holding the rollers against rotation.

tion in one direction, and necktie clamping means carried by each roller.

3. A necktie stretcher comprising a rectangular frame including side and end bars, 5 a supporting rod secured in the side bars near the lower end thereof, a pair of spaced superposed shafts secured in the side bars near the upper end thereof, a plurality of retaining rollers rotatably mounted on the 10 shafts, ratchet wheels carried by one end of each roller, jaws pivotally connected to the frame and detachably associated with

the ratchet wheels for holding the rollers against rotation in one direction, and clamping means arranged around each roller, said 15 clamping means adapted to secure one end of a tie to its roller, as and for the purpose specified.

In testimony whereof I affix my signature in presence of two witnesses.

EDWARD PIERSON.
